FENCE GUARD SUPPORT

Filed Oct. 4, 1928

Inventor
G. E. Armstrong

By *G. E. Armstrong Jr.*

Attorney

UNITED STATES PATENT OFFICE

GEORGE E. ARMSTRONG, OF WINDFALL, INDIANA, ASSIGNOR OF ONE-FOURTH TO ERNEST ARMSTRONG, ONE-FOURTH TO THEODORE ARMSTRONG, AND ONE-FOURTH TO FRANK ARMSTRONG, ALL OF WINDFALL, INDIANA

FENCE-GUARD SUPPORT

Application filed October 4, 1928. Serial No. 310,318.

The invention relates to means for supporting a guard wire at a distance from a wire fence to prevent the approach of cattle to and contact with the fence, and has for its 5 object the provision of an improved means for securing the guard wire in relationship with the fence comprising a bracket consisting of two separable members adapted to be secured to the wire fence, one of said members having an open supporting member to receive the guard wire, and provided with means to hold the other member in fixed relationship therewith and in closing position for the supporting member.

15 A further object of the invention is the provision of a guard wire support for wire fences adapted to be attached to the line wires of a fence where joined by a vertical stay wire, the supporting member having laterally extending hooks arranged on opposite sides of the two members, said hooks being adapted to be engaged with the line wires on opposite sides of the stay wire and to engage around the stay wire to prevent movement of the 20 supporting member relatively to the stay wire and longitudinally of the line wires.

The invention will be described in detail hereinafter and will be found illustrated in the accompanying drawings in which

30 Figure 1 is a view in perspective of a fragment of a conventional wire fence showing a guard wire and improved support in position.

Figures 2 and 3 are views in perspective of 35 the respective members of the support, and

Figure 4 is a view in perspective of the supporting portion of the bracket when assembled.

In the drawings similar reference characters are used to designate corresponding parts 40 in all of the views.

In Figure 1 is shown a fragment of a conventional wire fence, in which A indicates the fence post, B the line wires, and C the 45 vertical stay wires. In order to protect the wire fence from contact with live stock, such for instance as horses and cattle, it is customary to provide a guard wire D that is preferably of the barbed wire type, and held at a 50 distance from the wire fence so that the cat-

tle will contact with the barbed wire before reaching the fence and thus be prevented from contacting with the fence. The invention relates to an improved means for supporting the guard wire D in relation with 55 the fence, and comprises a bracket 1 that consists of two members, these members being rods 2 and 3. The member 2 forms the upper arm of the bracket and has at one of its ends a laterally extending hook member 4 and an 60 open loop member 5, the open loop member 5 being adapted to engage a line wire of the fence adjacent to one of the stay wires, and as shown in Figure 1, and the hook member 4 to engage around the joint formed by the 65 stay wire and the line wire. The other end of the rod 2 is rebent as shown at 6 to form an open hook 7 to receive the guard wire D, and is formed with a laterally coiled loop 8 adjacent to the hook member 7 to receive an 70 offset end 9 of the rod 3, said end 9 overlapping and closing the hook 7 to prevent casual 75 displacement of the guard wire D on the bracket 1.

10 is a laterally extending shoulder formed 75 by the offset end 9 that engages the rod 2 and coil 8 and serves to support the outer end of the rod 2 and the guard wire D. The other end of the rod 3 is formed with an open loop 80 11 that engages another of the line wires B under the wire engaged by the loop 5, and 12 indicates a terminal hook on the rod 3 that extends laterally therefrom in the opposite direction from the hook 4 and engages the same stay wire C as that engaged by the hook 4. 85 As shown in the drawings the loops 5 and 11 are engaged with the line wires of the fence on opposite sides of the stay wire C and the hooks 4 and 12 extending in opposite directions from their respective rods and also engaging the stay wire C to hold the bracket 1 from longitudinal movement on the line wires B and serves also to hold the bracket 1 at 90 right angles to the fence wires B and C.

What is claimed is:—

1. A guard wire support for fences, comprising a bracket having two members, means to secure said members to a fence, one of said members having a terminal hook adapted to support a guard wire, and a loop adapted to 95 100

receive an end of the other member and hold it engaged across the opening in the terminal hook to prevent casual displacement of the guard wire engaged therein.

5 2. A guard wire support for fences, comprising a bracket having arms engageable with the line wires and a stay wire of a wire fence, laterally extending hooks on said arms extending in opposite directions to engage the line wires on opposite sides of the stay wire to prevent longitudinal movement of the bracket on the line wires, and means on said bracket to support a guard wire.

10 3. A guard wire support for fences, comprising a bracket including two rods, each of said rods being provided with laterally extending hooks adapted to engage line wires and stay wires of a wire fence, the hooks on said members extending in opposite directions for engagement of the line wires on opposite sides of the stay wire to prevent longitudinal movement of the bracket on the line wires, means on one of said rods to engage a guard wire, and means on said rod to engage the other rod and hold it engaged therewith.

15 25 4. A guard wire support for fences, comprising a bracket having two separable members, means to secure said members to a fence, a hook on one member to receive the guard wire and a loop to receive the other member across said hook, and a shoulder on said other member engaging the first member to support it.

20 30 35 40 45 5. A guard wire support for fences, comprising a bracket including two rods, each of said rods having an open loop to engage line wires of a wire fence and laterally extending hooks to engage a stay wire, the hooks on the rods extending in opposite directions, one of said rods having its opposite end returned to form a hook to support a guard wire and provided with a loop adjacent to said hook, and the other rod having its free end offset to engage through the last mentioned loop and close said hook, and providing a shoulder to engage the first mentioned rod and support it.

In testimony whereof I affix my signature.
GEORGE E. ARMSTRONG.
